UNITED STATES PATENT OFFICE.

CHARLES F. PRESLAR, OF CINCINNATI, OHIO, ASSIGNOR TO THE PRESLAR-CRAWLEY MANUFACTURING CO., OF CINCINNATI, OHIO, A CORPORATION OF OHIO.

APPARATUS FOR SINKING TUBULAR WELLS.

SPECIFICATION forming part of Letters Patent No. 699,849, dated May 13, 1902.

Application filed August 27, 1901. Serial No. 73,448. (No model.)

To all whom it may concern:

Be it known that I, CHARLES F. PRESLAR, a citizen of the United States, residing at Cincinnati, in the county of Hamilton and State 5 of Ohio, have invented new and useful Improvements in Apparatus for Sinking Tubular Wells, of which the following is a specification.

My invention relates to well-sinking apparatus, and particularly to the class of transportable structures used in prospecting and drilling for water, oil, &c., its object being to improve the same in various particulars, as herein set forth.

15 My invention consists of the parts and the constructions and combinations of parts hereinafter described and claimed.

My invention is illustrated in the accompanying drawings, in which—

20 Figure 1 is a general side elevation of the machine complete, omitting the driving-motor, showing the derrick elevated. Fig. 2 is a perspective elevation of the supporting-frame detached. Fig. 3 is a side elevation 25 opposite to that shown in Fig. 1, showing the “derrick” lowered. Fig. 4 is a front elevation. Fig. 5 is a perspective view of a portion of the frame used as a unit for core-drilling in a confined space. Fig. 6 is a plan view

30 of the detachable core-drilling mechanism. Fig. 7 is a combined figure representing the shaft-supporting clamp in side and edge elevations; and Fig. 8 is an axial elevation of the main driving-pulley, showing the construction of the clutch device.

35 Referring now to the drawings, A designates the general supporting-frame of the machine, of rectangular form and mounted upon bearing-wheels *w* for self-transportation to its place of use. The frame A is constructed of

40 lower and upper side sills *a'* *a²* *a³* *a⁴*, corresponding end or cross sills *a⁵* *a⁶* *a⁷* *a⁸*, corner-uprights *b'* *b²* *b³* *b⁴*, and intermediate uprights *b⁵* *b⁶*, all of wrought-iron pipe, united at junctions by malleable-iron fittings *c*, similar in

45 form to ordinary “pipe-fittings.” The corner-uprights *b'* *b²* *b³* *b⁴* are extended upward a convenient distance and diagonally braced by braces *d* from the upright sills, and at their 50 upright extremities are provided with fittings

k' *k²* *k³* *k⁴*, constituting brackets for the pivotal engagement of the walking-beam (at rear) and the derrick, (in front,) as herein-after described. The various counter-shafts carrying the pulleys, gears, &c., constituting 55 the operative mechanism are arranged across the frame A in bearing-supports clamped to the sills and uprights, as hereinafter more particularly set forth. The frame thus constructed is durable and exceedingly light in 60 weight relatively to its resisting and supporting capacity, and is also sufficiently elastic to withstand the stresses of use and transportation over rough country without injury. It is also easily taken apart for transportation in pieces and as easily reconstructed in place with ordinary skill and ordinary pipe-fitters’ tools, all of which enables the machine to be used in otherwise inaccessible situations. Moreover, as will be readily understood, the pipe-sections are practically indestructible and at the angle junctions may be 65 screwed to the fittings, thereby providing solid joints of integral metal without the possibility of loosening through expansion and 70 contraction or through wear of bolts, bolt-holes, &c. The joint-fittings are also easily replaced when broken. The advantages of a light-weight frame of extraordinary strength are increased also by its elasticity, which enables it to withstand the jolting over rough 75 ground off the roads, as will be more clearly apparent in consideration of the load of mechanism carried upon the same. The general structural arrangement also permits a part 80 only of the frame to be used as a smaller unit, as illustrated in Fig. 2, in cases where want of space or other circumstances make it undesirable or impossible to employ the entire apparatus—as, for example, in a tunnel, cave, 85 or depression of the earth or where the operation is to be conducted from a float upon the water, &c. A more specific reference to this feature will be introduced later.

The counter-shafts, as already indicated, are 90 maintained in supporting-brackets clamped to the sills or uprights. As these supporting-brackets are all of essentially the same construction, the support shown in Fig. 6 will 95 serve as a type for all. It consists of a sub- 100

stantially-triangular supporting-block e , having a grooved base provided with screw-caps $e' e'$, adapting it to be clamped to one of the sills or uprights, and a cross-perforation e^2 at the apex, hollow and babbitted for the journal-bearing of a shaft. Bearings of substantially the same construction, differing in size and strength according to the use to be made of them, are provided for each shaft. These shafts in the complete apparatus shown consist of a general driving-shaft f , to which initial power is applied from a motor, (not shown,) shafts $g h$ for driving the main-hoist reel-shaft i and sand-pump reel-shaft j , respectively, a crank-shaft k for operating the walking-beam, (with an attendant fly-wheel shaft l for regulation,) and a removable shaft for driving the core-drill. The shaft f is located near the end of the frame farthest from the well and is supported above the sills $a^3 a^4$, and is the main driving-shaft to which the power is initially applied. It carries a normally loose driving-pulley p' , rotatively connected to or disconnected from the shaft by a friction-clutch device, a preferred construction of which is shown in Fig. 8, consisting, essentially, of radial plungers x , movable outward and inward in bearings upon radial arms y of a fixed hub y' by means of toggle-levers z , pivoted to a longitudinally-sliding collar, the plungers terminated by friction-blocks z' , contacting against the under side of the rim of the pulley p' . The particular construction of the device, independently of its use here, I have made the subject of a separate application pending herewith, and therefore need not further describe the same. The sliding collar operating the clutch device is operated by a bell-crank lever o' and a rod connection o^2 , Fig. 5, extending to the front of the machine-frame, and by these means the rotating power can be instantly or gradually engaged or disengaged. The shaft f also carries a fixed friction-pulley p^3 for operating the reels, a chain-gear for operating the walking-beam mechanism, and a belt-pulley p^3 for operating the core-drill, and, when necessary, a chain-gear for operating a pump, as in Fig. 5, and a capstan-pulley p^5 for general use. Below and at either side of the shaft f , in bearings suspended below the sills $a^3 a^4$, are the shafts $g h$, the first having a pinion and spur-gear connecting with a shaft i , supported in bearings upon the sills $a' a^2$, and the second having a chain-gear connection with a shaft j , mounted in bearings upon the uprights $b^5 b^6$. The shafts i and j carry windlasses $i' j'$ for rope, the former operating the sand-pump and the latter being the main hoist for lifting drills, &c. The shafts g and h are journaled at their forward ends in eccentric-blocks carried in their bracket-bearings e , which eccentrics project laterally through the bearings and are provided with cranks g' and h' , coupled to rods $g^3 h^3$, attached, respectively, to hand-levers $g^3 h^3$, mounted on the frame A at the front. By the manipula-

tion of the hand-levers friction-gears $g^4 h^4$ upon the shafts $g h$, respectively, are brought into contact with the fixed frictional pulley p^3 on shaft f , and the windlasses $i' j'$ are thus actuated, as desired. By a reverse movement of the levers $g^3 h^3$ the friction-gears $g^4 h^4$ are seated against fixed brake-shoes $g^5 h^5$, attached to the upright b^3 and the sill a' , respectively, whereby the unwinding of the windlasses may be safely regulated or instantly stopped, as desired.

The walking-beam is constructed of two parallel pipes b^{10} , pivotally connected at the rear to the uprights $b^3 b^4$ by the special fittings $k^3 k^4$, from which pivotal connection the pipes b^{10} extend forward to the front of the frame A. A wooden cross-brace b^{11} is secured to the pipes p^{10} near the front, to which brace pitmen k^2 are pivoted, extending downward to terminal cranks k' upon the shaft k , journaled in clamp-bearings e , suspended from the upper sills $a^3 a^4$. The shaft k is driven by a chain belt from the chain-gear p^3 on the initial counter-shaft f , and to regulate its motion and that of the walking-beam it carries a spur-gear k^3 , meshing with a spur-pinion l' upon the shaft l , journaled in adjacent bearings clamped to the sills $a^3 a^4$ and carrying a fly-wheel l^3 .

The derrick N is built of two side pieces $n n$, suitably braced across, converging upwardly, and provided at the lower ends by special fittings n' , pivoted to fittings m^2 , secured to the uprights $b^1 b^2$ in such manner that the fittings n' socket into the upper ends of the uprights when elevated, as shown in Fig. 1, in which position they are held by diagonal braces n^3 , bolted to the upper ends of the uprights $b^3 b^4$. Pulleys p^6 at the top of the derrick N on the cross-piece b^{11} and p^8 and on a cross-bar connecting the fittings $m^3 m^4$ are provided for the elevating-rope from the reel j' , used in operating or lifting the drill. The reel being held stationary, the vertical movements of the walking-beam cause a relative lengthening or shortening of the drill-suspending rope r' , which lifts and drops the drill alternately. The rope r^2 from the sand-pump reel i' passes directly to and over a pulley p^9 at the top of the derrick adjacent to the pulley p^6 , and thence directly downward to engagement with a sand-pump or with the rotary drill s' . (Shown in Fig. 1.)

In connection with these mechanisms I have provided a core-drilling device which may be attached to and detached from the machine, as desired. This is illustrated more particularly in Figs. 1, 3, 5, and 6, and consists of a frame u , formed to contain, in suitable bearings for rotation, a bevel-pinion v' , set upon a hollow sleeve v^2 , journaled in said bearings, and a lateral driving-shaft v^3 , having a corresponding bevel-pinion (miter-gear) v^4 in constant mesh with the pinion v' , and a driving-pulley v^5 , the latter upon a terminal projection of the shaft beyond the frame m . The frame u is secured to pipes or bars u' ,

which upon occasion are telescoped into the front ends of the sills a^3 a^4 of the general supporting-frame of the machine and held by set-screws, thus bringing the hollow sleeve 5 v^2 in front of the machine in the projected vertical axis of the well. The drill s' to be rotated passes through the sleeve v^2 and is suitably engaged therewith in any convenient manner for its due rotation. The driving-shaft v^3 is rotated by a direct belt connection between its pulley v^5 and a corresponding pulley p^4 on the main shaft f , the belt being put on or off as required. During 10 operation the rotation of the drill may be instantaneously stopped or started by engagement or disengagement of the main pulley of the main shaft through manipulation of the clutch devices, and the same is true of any other of the operative mechanisms. When not in use, 15 the frame u is taken off or detached at one side and turned up vertically upon its opposite supporting-bar u' as a hinge.

The modified arrangement of mechanisms upon the frame in Fig. 5 will serve to illustrate the freedom with which such changes may be made as a functional advantage of the frame structure and shaft-supports. Such a unit is used, for example, in a mine or at the bottom of a shaft and driven from 20 a motor at the earth surface. Ordinarily the motor—for example, a gasoline-engine—may rest upon the rear extensions of the sills a' a^2 , driving a shaft w' , as shown in Fig. 1.

I claim and desire to secure by Letters Patent of the United States—

1. In a well-sinking apparatus a rectangular supporting-frame composed of an upper and lower series of horizontal tubular sills connected by vertical tubular uprights united 40 thereto by "pipe-fittings" and with corner-uprights extended above the uppermost horizontal sills, in combination with the derrick consisting of two side pieces, one at each side of the frame and provided with fittings extending in the direction of the length of the 45 said side pieces and provided with terminal studs, said forward-extended corner-uprights having sockets to receive said studs when the derrick is in its elevated position, and 50 said fittings pivotally mounted to said forward uprights substantially as set forth.

2. In a well-sinking apparatus, a rectangular tubular supporting-frame substantially as described and including corner-uprights, in combination with a derrick composed of two side members converging upward and having fittings at their lower ends and forming longitudinal extensions of said ends one of said side pieces pivotally mounted to each of the corner-uprights of the main frame and 55 said fittings having terminal studs to fit sockets in the upper extremities of the front uprights, when the derrick is in elevated position, a walking-beam having one end pivotally connected to the extended portions of the rear corner-uprights and extending forward between the extended portions of the front uprights substantially as set forth.

3. In a well-sinking apparatus of the character indicated, the combination with a frame 70 composed of horizontal spaced metallic tubes and means uniting them at the ends, and tubular corner-posts, of a shaft-support consisting essentially of a triangular block on each of a pair of tubes and having a journal-bearing at the apex and perpendicular to the plane of the triangle, a groove at the base and in the plane of the triangle and one or more correspondingly-grooved caps removably united thereto with screws or bolts to 75 constitute a clamp connection for the shaft-support upon a tubular sill or upright of a frame, substantially as set forth.

4. The combination with a main frame having sockets at the front, of a removable "revolving-head" device embodying a frame containing the revolving head, said last-named frame fixed to bars or tubes adapted to telescope into said sockets of the main frame, a driving-shaft engaging the revolving head 90 by bevel-gearing and clamping-caps adapted to secure the device removably upon sills or extensions of the main supporting-frame of the well-sinking apparatus, substantially as set forth. 95

In testimony whereof I have hereunto set my hand in presence of two subscribing witnesses.

CHARLES F. PRESLAR.
